Robert C. Benton and David A. Bauchspies, State College, Pa., assignors to Centre Circuits, Inc., State College, Pa., a corporation of Pennsylvania

Filed Feb. 8, 1961, Ser. No. 87,861

4 Claims. (Cl. 134—63)

The present application relates to a machine for spray etching parts such as thin metal webs or panels, and also metal clad panels. More particularly, it relates to a horizontal roller table structure for conveying parts being processed through the machine.

Articles in the category of thin metal webs and other parts suitable to be conveyed through and processed by etching machines include electric motor laminations, television masks, intricate flat spring steel parts, transformer laminations, and microwave attenuators, each being provided with exposed areas and acid resist masked areas. The etchant fluid forms perforations in the exposed areas only. The metal clad panels referred to are predominantly printed circuit boards, these boards generally having both sides provided with metal cladding on a flat backing, usually an insulative panel. An acid resist pattern on the metal preserves the metal circuit portions which are to be retained on the insulative panel.

It is found in practice that spray etching work is more uniformly done in many cases with the work in a horizontal position rather than in a vertical plane. Even so, etchant tends to attack the topside surface and the underside surface of the work at a different rate, with the underside being etched faster. The chief reason is that inactive etchant collects and stands in a topside layer, which must always preliminarily be scrubbed away by the oncoming sprays, whereas the etchant drips naturally from the underside surface so as to rapidly re-expose it unimpededly to the lowermost sprays. Also, to mention another of the reasons, it is noted that the static head on the lowermost sprays is slightly higher giving their droplets slightly higher velocity of impingement than the uppermost sprays produce at their elevation.

The present horizontal conveyor is provided with a plurality of rollers to overcome the above difference in inequality. Proper roller distribution in accordance with this invention tends to balance the rates of etching by blanking off portions of the underside surface of the panels. Moreover, no racks are necessary where the articles processed are individual panels, being as the roller distribution provides a plurality of supporting points on which the articles readily ride irrespective of whether the series of articles is formed in a continuous web or else separated as individual articles. Live axles are provided for carrying these rollers in rows, and the axles establish a separate fixed axis of rotation for each such row.

A feature of this conveyor is the incorporation therein of novel fluid traps at its points of entry and exit from each spray compartment or chamber of the spray etching machine. These traps prevent carry-over of etchant liquid or rinse liquid between chambers and also prevent escape of the fluids beyond the outermost chambers.

As above indicated, an etching machine embodying the present conveyor is primarily adapted for the handling and processing of webs or panels presenting metal surfaces on both sides. It is understood according to the broader principles hereof that the invention will effectively etch single-sided work, i.e., a panel or web presenting metal to be etched at one side only.

Further features, objects and advantages are either specifically pointed out or will become apparent when, for a better understanding of the invention, reference is

2

made to the following written description taken in conjunction with the accompanying drawings in which:

FIGURES 1 and 2 are longitudinal side elevational and top plan views, respectively, of an etcher with a conveyor therein embodying the present invention;

FIGURE 3 is a fragmentary portion of FIGURE 2 drawn to enlarged scale;

FIGURE 4 is a transverse elevational view taken along the lines IV—IV of FIGURE 1;

FIGURE 5 is a longitudinal view in side elevation taken along the lines V—V of FIGURE 4;

FIGURES 6 and 7 are elevational views transversely and longitudinally, respectively, taken along the section lines VI—VI and VII—VII of FIGURE 2; and

FIGURE 8 is a fragmentary showing in side elevation of a double tiered modification of the conveyor invention of FIGURE 1.

More particularly, in FIGURES 1 and 2 of the drawings, a spray etching machine is shown having a base 10 which by means of a set of upright pillars 12 and 14 supports a loading station 16 at one end onto which incoming articles 18a are placed. By means of upright pillars 20 and 22 thereon, the base 10 provides an unloading station at the other end consisting of a receiving tray 24 for the etched articles 18b being discharged.

Intermediate the end loading station 16 and the end unloading station, a series of tandem connected spray chambers is located on the base 10 consisting of a main etchant chamber 26, a first rinse chamber 28 and a final rinse chamber 30. Two side guide panels 32 joined by a cover 34 at the top form an entry housing on the entry side of the etchant chamber 26. Four traps 36 are provided, one at a location in the entry wall of the chamber 26 in alignment with the housing 34, another in a division wall 38 between the chambers 26 and 28, another in a division wall 39 between the chambers 28 and 30, and the last trap 36 in the exit wall 40 of the chamber 30. These traps actually constitute a rotary baffle system which operates so that spray and fume carry-out is minimized.

A motor-operated roller table 42 extending in a horizontal plane between the end loading station 16 and the end unloading station conveys the articles from the position 18a through the series of chambers to the discharge position 18b. A continuously running, external drive motor 44 is connected through a pinion and gear drive 46 to operate the individual rollers 48 of the roller table 42. The motor 44 is supported by a cross member carried between the uprights 12 and 14.

Turning of the rollers 48 in the proper direction on their fixed axes causes articles on the conveyor 42 to move in a horizontal path from left to right as viewed in FIGURES 1 and 2. Within chamber 26, these articles pass between groups of spray nozzles, the lowermost ones 50

55 of which are directed transversely upwardly so as to discharge in the plane of the conveyor 42. The uppermost nozzles 52 discharge downwardly in a transverse direction to the horizontal path of movement of the articles. These groups of nozzles are supplied from the outlet 54 from one

60 or more recirculating pumps 56 and leading through connections, not shown, to the manifolds for the nozzles. Each pump 56 has a suction line 58 and is driven from a pedestal mounted motor 60 all as more completely shown and described in Bauchspies application, Serial No.

6,899, filed February 5, 1960, and now abandoned. Preferably, two of the motor-driven pumps 56 are employed as shown in a plan view of FIGURE 2, enabling the uppermost nozzles 52 to have a separately controllable source of supply from the source of the lowermost nozzles 50, in case single-sided work is to be processed.

The etchant fluid supply 62 collected in the bottom of

the chamber 26 is continually replenished by recovering spray from the nozzles which is then recirculated. A heater 64 keeps the supply of etchant at the proper temperature. If copper is the metal being etched from the articles, one suitable etchant solution is ferric chloride.

A water rinse recirculation system within the chamber 23 consists of spray nozzles 66 and 68 above and below the horizontal path of the conveyor 42 and a pump circulation system, not shown, including a pump suction line 70 whereby pressure induced sprays are forced through the nozzles 66 and 68. The final rinse chamber 30 contained similar nozzles 72 and 74, along with a separate pump system, not shown, including a pump suction line 76.

In FIGURES 3, 4 and 5, the horizontal conveyor table 42 provided with rows of the rollers 48 has full length walking beams 78 and 80 disposed one on each side. The walking beams 78 and 80 are supported at each end by common cross shafts, one of which is shown at 82a in FIGURE 3 and each carrying a crank 84 at each end with the throw journaled in a hole in the walking beam at that end. As viewed along the axis of the shaft 82a, the cranks 84 are offset or phased at 90° angularity to one another to insure unidirectional movement of the beams in a curved path; one or more intermediate cross shafts 82b are provided to furnish intermediate support for the walking beams 78 and 80, and they carry similarly phased cranks 84.

The pinion and gear connection 46 from the drive motor 44 rotates the shaft 82a whose cranks 84 force the walking beams 78 and 80 each to move in a path closing on itself and circular in nature as indicated in FIGURE 5. An arrow is used to indicate the resulting direction of material movement in FIGURES 3, 5, and other figures of the drawings. Roller carrying shafts 86 have cranks 88 provided at one end only and connected to the walking beam 78 at that end so that the shafts 82a, 82b and 86 rotate in unison; the throw of the cranks 86 has the same phase angularity and throw as the cranks 84 journaled in the walking beam 78. These shafts form live axles for the rollers and have fixed center to center distances M which exceed the individual roller diameters and which are established by equally spaced shaft bearing holes provided in a pair of stationary bearing bars 90. The shafts thus space the rollers 48 apart so that the rows do not overlap in the longitudinal direction, and in the transverse direction, the rollers 48 of the row of rollers on each shaft 86 are equally spaced apart by a distance N.

In FIGURE 4, the distribution of the uppermost nozzles 52 is such as to provide an overlapping spray pattern on the surface of each article 18 against which the spray impinges; the distribution of the lowermost nozzles 50 provides an overlapping spray pattern on the undersurface surface of the articles 18 being sprayed. In the latter regard, the close arrangement of the conveyor rollers 48 cause the lowermost sprays, when discharged in the plane of rollers, to encounter a partial masking or blocking effect, thus slowing down the undersurface etching rate to an appreciable extent. In case the presence of the rollers 48 combined along with other factors overcompensates for the slowness of the uppermost nozzles in their etching rate, then in that case where the rate becomes relatively excessive it can be reduced by sliding out a retracted set of baffles 91 (FIGURE 1); the baffles are adjustably mounted in the chamber 26 and will block off the path of spray from an appreciable number of the uppermost nozzles 52. As a means of keeping the blocking effect from becoming too significant, the rollers 48 are each one beveled as indicated at 92 at the periphery to minimize its area of contact with the underside of the panel and thus stay within limits of a narrow strip path. Moreover, the rollers of alternating ones of the rows are aligned in one vertical plane only as indicated at 94 in FIGURE 3

so that their strips of contact will be staggered. The rollers in each of the remaining rows of rollers are located in a plane 96 midway (i.e., $N/2$) between the nearest two rollers of the immediately preceding row.

5 The rollers 48 are plastic and are made fast at the points indicated on their respective carrying shafts 86 by means of a press fit; at their periphery they carry a set of teeth 98 which are rotated as the shaft 86 rotates. These teeth 98 are effective in the event that a warped article 10 having a down-turned front edge tends to hang between rows of rollers; in that event, an upcoming tooth 98 would engage the down-turned leading edge at the article position 18c and raise it to the solid line position 18 of FIGURE 5 in the plane of the tops of the rollers so as to 15 keep the article progressing horizontally.

In FIGURES 6 and 7, each oncoming article 18 entering a trap 36 encounters a full width upper roll 100 and a full width lower roll 102 which operatively engage it very lightly, if at all, on the topside and also on the underside, respectively. The upper roll 100 is capable of limited vertical movement in the direction of the fixed axis lower roll 102 and can be preloaded to a minor extent through adjustable weak springs 104 and light bearing blocks forming an adjustment mechanism. A full width 20 combined baffle and wiper 106 is supported along its bottom edge and presents a lip at its free upper edge engaging the lower roll 102. The rolls and baffles are housed in a box formed by two U-shaped channels 107 which 25 confront one another across the path of movement of the articles 18 to form a box; the baffle 106 is approximately in the vertical plane 108 of the adjacent division wall which supports the trap 36.

A drain tube 110 communicates with the chamber at 30 one side of said plane 108 for returning liquid wiped by the rolls 100 and 102 for re-collection in that chamber. A similar drain 112 establishes communication with the chamber at the opposite side of the plane 108 for returning liquid that splashes into the channels 107 so as to 35 make it available for recirculation in that chamber. The drain 110 is omitted from the specific trap 36 within the entry housing 34 and the drain 112 is omitted from the trap 36 in the wall 40 on the exit side of the final rinse chamber 30; the baffle 106 is not essential in these 40 two traps and is omitted if desired.

45 According to the modification of FIGURE 8, a double tiered arrangement is readily constructed using identical vertically spaced apart roller tables 142 to define two horizontal parallel paths instead of one through the spray etching machine. The capacity is twice the capacity of the machine of FIGURE 1, although other than for the 50 following exceptions, the two machines are identical.

In the spray etching chamber 126 in FIGURE 8, the lowermost group of up-turned nozzles is indicated at 150, 55 the uppermost group of down-turned nozzles is indicated at 152, and the center group 151 is arranged to spray simultaneously upwardly and downwardly.

Traps 136 are located in accordance with the previous 60 embodiment and the first rinse chamber 128 contains a lowermost set of nozzles 166, an uppermost set of nozzles 168 together with an upwardly and downwardly spraying set of nozzles 167 disposed between the two conveyor tables 142. The final rinse chamber 130 is separated by a division wall 139 from the first rinse chamber 128 65 and has an end wall 140; the chamber 130 contains a lowermost set of nozzles 172, and an uppermost set of nozzles 174 together with a set of upwardly and downwardly spraying nozzles 173.

70 The uppermost one of the conveyors 142 can be extended at one end beyond the corresponding end of the other conveyor 142 at the end unloading station in case the finished articles from the two paths are desired to be kept separated.

75 Following is an example of the specifications, dimen-

sions, and materials used in the foregoing embodiments of our etching machine:

Over-all length of machine	134 inches.
Over-all height	52 inches.
Nozzle pressure — uppermost nozzles 52	7 p.s.i.
Nozzle pressure — lowermost nozzles 50	10 p.s.i.
Discharge pressure—pumps 56	13 p.s.i.
Number of washer (rinse) sections	2.
Shafts 82a, 82b and 86	titanium.
Walls of chambers 26, 28 and 30	polyvinyl chloride.
Etching capacity	225 square feet per hour.
(Double tiered)	450 square feet per hour.
Sump capacity in chamber 26	40 gallons.
Sump temperature	130° F. (ferric chloride).
Teeth 98 on each roller 48	10 teeth.
Roller 48 diameter	7/8".
Roller distribution dimension N	1 inch to 4 inches.
Roller distribution dimension M	1 inch to 4 inches.
Combined baffle and wiper 106	plasticized polyvinyl chloride strip 1/16" thick.
Maximum width of work to be etched	22 inches.

Variations within the spirit and scope of the invention described are equally comprehended by the foregoing description.

We claim:

1. In a spray etcher having an end loading station and an end unloading station, the combination of spray chambers intermediate said stations and provided with liquid spraying devices therein, said spray chambers comprising etchant spray chamber means in which pressure-induced sprays of liquid etchant are confined and adjacent rinse chamber means in which pressure-induced sprays of a rinse liquid are confined, means for supporting panels to be etched comprising a horizontal roller table extending from one end station to the other for conveying panels in a path through said spray chambers, drive means connected for simultaneously rotating the rollers of said table, first and second box-shaped trap means carried respectively at the path entry points of said etchant spray chamber means and said rinse chamber means and third and fourth box-shaped trap means carried respectively at the path exit points of said etchant spray chamber means and said rinse chamber means, said second and third box-shaped trap means consisting of portions of the same liquid-blocking trap located at a point in a division wall between the chambers, and containing an upper and a lower roll in engagement with the entering and exiting panels for blocking the escape of liquid being sprayed on panels in said chambers, and a pair of drain openings disposed one on each side of the rolls in said liquid-blocking trap and each communicating with the chamber at that side for returning trapped liquid thereto for recirculation.

2. In a spray etcher, means in the path of a series of horizontal panels being conveyed therethrough comprising spray chambers in tandem but divided from one another, said spray chambers each provided with spraying means therein and together having a box-shaped trap at the point of a division wall between same, a full width upper and a full width roll in said trap operatively engageable with a panel passing therethrough, a baffle wall

in said box-shaped trap substantially in the plane of said division wall and wipedly engaging one of said rolls for substantially the full dimension of said roll, and drain openings in the trap disposed one on each side of said baffle wall and each communicating with the chamber on that side for returning liquid thereto for recirculation.

3. In a panel spray etcher having an end loading station and an end unloading station, means for movingly supporting panels to be etched comprising a horizontal roller table extending from one end station to the other for conveying panels in a flat path therebetween, chamber means surrounding a portion of said path, and comprising vertically spaced apart groups of etchant spray nozzles disposed transversely to said path within the chamber means for spraying panels on the top side and underside surfaces simultaneously, the lowermost group of nozzles discharging upwardly through the plane of the table so as to impinge etchant on the confronting underside surface of said panels, means connected for rotating the rollers of said table in unison, comprising drive means disposed on at least one longitudinal side of said table, power delivery means for applying power to drive said drive means, there being a plurality of said table rollers, and shafts disposed transversely in said table and carrying said plurality of table rollers fast thereto, said shafts connected to said drive means for rotating said rollers in unison all at the same speed as aforesaid and under positive drive, said rollers being provided with a set of teeth in the periphery of each and dentally engageable with the leading edge of any advancing panel having a downturned front edge to insure raising of said edge at least to the plane of the tops of the rollers.

4. In a panel spray etcher having an end loading station and an end unloading station, means for movingly supporting panels to be etched comprising a horizontal roller table extending from one end station to the other for conveying panels in a flat path therebetween, spray chamber means surrounding a portion of said path for spraying panels on the topside and underside surfaces simultaneously, and a power drive connected for simultaneously rotating the rollers of said table comprising walking beam means disposed one on each longitudinal side of said table, power delivery means for applying power to drive said walking beam means in an endless closed path, and crank carrying shafts disposed transversely in said table and each carrying a plurality of the table rollers fast thereto and connected through the crank thereof to one of said walking beam means for rotating said rollers under positive drive, said rollers being notched to provide a set of teeth in the periphery of each and dentally engageable with the leading edge of any advancing panel having a downturned front edge to insure raising of the said edge at least to the plane of the tops of the rollers.
